PAPER BAG

**Harold Smithwick, Scarsdale, N. Y., assignor to
Continental Paper & Bag Corporation, New
York, N. Y., a corporation of Delaware**

Application September 3, 1930, Serial No. 479,480

3 Claims. (Cl. 229—54)

The present invention relates to improvements in carrier bags and more particularly to a light paper bag of the open top type which is provided with a cord or the like which provides a pair of flexible handles at the top of the bag to facilitate the carrying of the bag, and which by passing under the bottom of the bag serves to support the weight of the contents of the bag and thereby increases the load capacity of the bag.

10 It is the object of the present invention to simplify the construction of the bag and cord.

Another object is to dispose the cord on the bag in such a manner that while the two parts of the cord that pass under the bag will be so spaced as to afford the maximum support for the load or contents of the bag, the parts forming the handles will have their vertical parts spaced more closely with the result that they will form comfortable handles and will not tend to tear or 15 mar the bag. This I accomplish generally by disposing the two strands of the cord that lie against each side wall of the bag in such a manner that they converge toward the top of the bag. By this arrangement the loaded bag is 20 supported by the cords passing under the bottom of the bag so that the two parallel strands are spaced from each other on the bottom of the bag much more than the parts that form each handle.

25 More particularly I prefer to slant the strands lying against the sides of the bag so that when the bag is loaded the distance between the strands under the bottom will equal approximately one-half the width of the bag in its distended condition. By this arrangement of the cord on the bag the load, which consists largely of small items or parcels, will be properly supported by the 30 cord.

The invention will be more clearly understood 35 by reference to the accompanying drawing, in which

Figure 1 is a side view of the folded bag.

Figure 2 is a longitudinal sectional view of the folded bag.

40 Figure 3 is a longitudinal sectional view of the bag when distended.

In the drawing 10 represents the bag having side walls 11 and 12 and bottom 13. While as shown the bottom 13, when folded, forms a gusset, it will be understood that the present invention may be applied to other types of bags.

45 Each side wall of the bag is provided with a pair of perforations 14 near its top and with a pair of perforations 15 near its bottom. The endless cord 16 is strung through the openings so

that the portions 17 form a pair of substantially parallel strands under the bottom 13 when the bag is distended and loaded. The cord also forms the carrying handles 18 at the top of the bag.

5 The perforations 14 are so spaced that the handles conform to the hand and do not tend to tear the bag. The distance between the perforations 15 is greater than that between the perforations 14 so that the strands 17 lying under the bottom of the bag are so spaced that they will 10 effectively support the load. More specifically, I prefer to space the perforations 15 so that the strands 17 will each lie on the bottom of the bag along a line removed from the corresponding edge of the bag approximately one quarter the width 15 of the bag. By this means each half of the cord supports half the contents of the bag at approximately its midpoint.

In order to clearly illustrate the principle of 20 the invention the strands 19 which lie slanted against the side walls of the bag are shown with the slant somewhat exaggerated. It will be understood, however, that the main feature of the invention resides in disposing the strands 17 25 so that they are spread over the bottom of the bag to a greater extent than is obtained in construction where the strands 19 are parallel.

While the present invention may be applied 30 to any type of bag, the invention as shown is preferably applied to the type of bag shown for the reason that it affords ready access to the interior of the bag both during loading and unloading and for the further reason that the gusset shaped infolded bottom permits the bag and its 35 bottom to open readily as it is loaded and obviates the necessity, common in other types of carrier bags, of spreading open the bottom of the bag before it is loaded.

40 What is claimed is:—

1. In combination, a collapsible paper bag having side walls adapted to fall against each other and a square bottom foldable inward between the side walls along a line that extends substantially centrally of the bottom, each of said side walls having a pair of horizontally spaced perforations near the top thereof and a pair of horizontally spaced perforations near the bottom thereof, the distance between said last mentioned pair of perforations being substantially greater than the distance between the first mentioned pair of perforations, and an endless cord strung through said perforations and extending around the bottom of the bag, said cord forming handles at the 45 top of the bag, having parts lying flat against 50 the bottom of the bag.

the walls of the bag along lines convergent towards the top of the bag, and having parts extending across the bottom of the bag in widely spaced, substantially parallel relation.

- 5 2. In combination, a collapsible paper bag having side walls adapted to fall against each other and a square bottom foldable inward between the side walls along a line that extends substantially centrally of the bottom, each of said side walls 10 having a pair of horizontally spaced perforations near the top thereof and a pair of horizontally spaced perforations near the bottom thereof, the distance between said last mentioned pair of perforations being substantially greater than the distance between the first mentioned pair of perforations, and an endless cord strung through said perforations and extending around the bottom of the bag, said cord forming handles at the 15 top of the bag, having parts lying flat against the

wall of the bag along lines convergent towards the top of the bag, and having parts extending across the bottom of the bag in widely spaced, substantially parallel relation.

- 5 3. In combination, a collapsible bag having side walls adapted to fall against each other and an infolded square bottom, said side walls having perforations and an endless cord strung through said perforations, said cord having parts lying flat against the walls of the bag along lines convergent towards the top of the bag and parts extending freely around the bottom of the bag along lines spaced from the corresponding edges of the bag and substantially parallel to one another, and said cord forming handles at the top of the bag whereby the bag is readily distended during loading. 10 15
